(57) **CLAIM**

The ornamental design for a medical dressing, as shown and described.

DESCRIPTION

FIG. 1 is a top perspective view of a medical dressing attached to a carrier layer;

FIG. 2 is a top perspective view of a medical dressing;

FIG. 3 is a front view of a medical dressing;

FIG. 4 is a rear view of a medical dressing;

FIG. 5 is a left side view of a medical dressing;

FIG. 6 is a right side view of a medical dressing;

FIG. 7 is a top view of a medical dressing;

FIG. 8 is a bottom view of a medical dressing; and,

FIG. 9 is a top perspective view of a medical dressing in a position of use.

In the drawings, the broken lines show portions of a medical dressing that form no part of the claim.
